TRAIN CONTROL

Filed Nov. 26, 1924

UNITED STATES PATENT OFFICE.

WILLIAM D. HAILES, OF ROCHESTER, NEW YORK, ASSIGNOR TO GENERAL RAILWAY SIGNAL COMPANY, OF ROCHESTER, NEW YORK.

TRAIN CONTROL

Application filed November 26, 1924. Serial No. 752,338.

This invention relates to automatic train control systems, and more particularly to an improved amplifier for use in connection with automatic train control systems of the continuous inductive type.

In modern train control practice suitable means must be provided to communicate control influences from the trackway to a moving vehicle. In the type of system embodying the present invention, this communication is accomplished by means of two alternating currents flowing in the track rails or other suitable trackway conductors, and inducing corresponding currents in collecting coils carried by the vehicle. The alternating control currents flowing in the track rails are displaced in phase relation, and the various distinctive influences are transmitted by means of the reversal of the instantaneous polarity of one of these currents, and the absence of either one or both of these currents.

In the practical application of such a system of the continuous inductive type to railways, it is found that in order to maintain the proper mechanical clearance between the car-carried receivers and the trackway equipment, the air gap through which the inductive influences must act is comparatively large, and for this reason the current induced in the car-carried receivers is very small. In order that this weak current may properly operate the car-carried equipment, it is essential that some amplifying means be used, and the vacuum tube or audion type of amplifier has been found to be best suited for this purpose.

In the type of amplifier now in use, two sets of vacuum tubes or audions are used to amplify the control currents collected by the two sets of receiving coils, these tubes being supplied with plate current from a common source usually a suitable direct current generator or dynamotor, and their filaments being heated by a common battery or other suitable source of energy. The output of these two sets of audions is impressed upon the two phase windings of a suitable polyphase relay which operates the car-carried control apparatus. In the usual type of amplifier, it has been found that the energization of one of these sets of receiving coils alone produces a variation or fluctuation in the plate voltages supplied to the amplifier, and that this variation in plate voltage results in a variation in the plate current in the first

tube of the de-energized amplifier and, when a transformer is used in the plate circuit, impresses a variation in grid potential upon the second tube of this amplifier, and so gives rise to an alternating current in the output circuit and a consequent flow of current in the phase of the relay which should be de-energized. For various reasons, this current in the presumably de-energized phase of the relay may not be in phase with the current in the energized phase, and if these two currents are out of phase, a torque in the relay will result, sometimes causing a false operation thereof. The fluctuation of the plate voltage may arise from commutator ripples as well as from variation in loads.

With the above and other considerations in mind, it is proposed in accordance with the present invention to provide an improved amplifier for use in connection with a continuous inductive train control system in which a fluctuation in the plate voltage will not result in a false energization of the relay.

Other objects, advantages and characteristic features of the present invention will become apparent as the description thereof progresses.

In the drawings, the amplifier embodying the present invention has been shown in a diagrammatic and conventional manner, together with a simplified showing of the trackway and car-carried equipment of a typical train control system of the continuous inductive type.

The amplifier comprising the present invention may be used with any suitable type of trackway circuits and control devices, the system shown being of the usual three-position type embodying two control currents; the track phase current, flowing in the two track rails in series, and the line phase current, flowing in the two track rails in multiple. These control currents are impressed on the track rails of the usual insulated blocks, of which the block I and the ends of the two adjacent blocks H and J have been shown, these currents being supplied from a transmission line 1 through transformers 2 and 3, and being controlled by the usual track relays 4 located at the entrance end of the blocks. A phase displacement is maintained between the track and line phase currents flowing in the track rails by means of suitable resistances or impedance units, such as the impedance coils 6 as shown in the track phase

circuits. The track relays 4 are energized from the usual track batteries 5, located at the exit ends of the blocks, the currents from these batteries being shunted away from each track 5 relay when a train is located in the block with which this relay is associated by the wheels and axles of such train. From an inspection of the drawings, it is evident that the de-energization of the track relay 4 of a given 10 block will cause a reversal of the instantaneous polarity of the line phase current in the block next in the rear with reference to the normal direction of traffic which is indicated by the arrow.

15 A railway vehicle has been conventionally represented in the block H by the wheels and axles 7. This vehicle is provided with the usual collecting or receiving coils, represented at 8 and 9, which are mounted with or without 20 iron cores and in inductive relation to the track rails. The track and line phase control currents flowing in the track rails induce corresponding voltages in the receiving coils, and these voltages are impressed on the input 25 circuits of the two amplifiers which comprise the present invention. The output circuits of these amplifiers are connected to the two windings 10 and 11 of a polyphase car relay MR of the type now common in the train control 30 practice.

The relay MR may be used to operate suitable contact fingers such as the fingers 12 and 13 shown, and to control circuits for various suitable car-carried apparatus by means of 35 these fingers and their associated stationary contacts. In the present instance, cab signals G, Y and R have been shown, representing clear, caution and danger traffic conditions, these cab signals being preferably in 40 the form of lights or other visual indications, and being controlled by the contact finger 12 of the relay MR through circuits which are obvious from the drawings. The progress 45 of the vehicle may be controlled in any suitable manner by means of the well known devices used for this purpose in train control systems. For the purpose of illustration, two brake control actuating devices HB and LB have been shown, it being assumed that 50 the device HB acts in some suitable manner to impose a medium speed restriction upon the de-energization of a circuit through its windings, and that the device LB acts to impose a minimum speed restriction upon the de-55 energization of its circuit. The circuits for the brake control device are controlled by the contact finger 13 of the relay MR and these circuits may be readily traced in the drawings.

60 Referring now more particularly to the amplifying device comprising the present invention, this device is composed of two amplifiers, of two stages each, one amplifier T being arranged to amplify the track phase voltages induced in the coils 8, and the other

amplifier L to amplify the line phase voltages induced in the coils 9. As these amplifiers are identical in every detail, a description of the line phase amplifier L only will be given, the corresponding parts of the track 70 phase amplifier T being designated by like reference characters having distinctive exponents.

The voltage induced in the receiving coils 9 is impressed across the grid and filament 75 of the first tube 14 through a circuit which may be traced as follows:—From the receiving coils 9, wires 15 and 16 to the grid 17 of the tube 14, through the filament 18, through the resistance unit 19 and the ballast lamp 20 in series, wires 21, 22 and 23 to the receiving coils 9. The receiving coils 9 are tuned to resonance for maximum voltage at the frequency of the alternating control current by means of the condenser 24 connected across these coils as clearly shown. The filaments 18 and 25 of the two audions 14 and 26 are connected in series and are heated by a single battery 27 through a circuit including the usual current limiting resistance 19 and the ballast lamp 20, which circuit is obvious from the drawings. A voltage is impressed between the filaments 18 and 25 and the plates 28 and 29 of the two tubes 14 and 26 by means of a direct 95 current generator G, through parallel circuits including the iron core impedance coils 30 and 31 as clearly shown. The impedance of the coils 30 and 31 is of a high value, these coil impedances being preferably from 7 to 100 10 times the value of the internal impedance of the tubes for reasons which will become apparent as the description of the amplifier progresses. It is evident that the filaments and the plate circuits of the tubes 14¹ and 105 26¹ of the track phase amplifier T are also supplied with energy from the battery 27 and the generator G.

The output of the first tube 14 is impressed upon the primary winding 38 of a suitable 110 transformer, in the present instance, an autotransformer 33, through a circuit which is traceable as follows:—From the plate 28 of the tube 14, wires 34 and 35, blocking condenser 36, wire 37, primary winding 38 of the 115 autotransformer 33, wires 39, 40 and 21, ballast lamp 20, and resistance 19 to the filament 18 of the tube 14. The secondary winding 120 of the transformer 33 is connected to the grid circuit of the second tube 26 through the following circuit:—From the grid 32 of the tube 26, wires 42 and 43, through the secondary winding 41 of the autotransformer 33, wires 39, 40 and 21, ballast lamp 20 and resistance 19, the filament 18 of the tube 14, 125 and wire 44 to the filament 25 of the tube 26. The secondary winding of the transformer 33 is tuned to resonance at the frequency of the control current by means of the condenser 51, connected as shown, this tuning being 130

particularly advantageous when a generator is used in place of the battery 27 to supply the filament current. When a filament generator is used fluctuations in the filament current are sometimes produced by the commutator ripples of this generator, and these fluctuations may produce a false operation of the relays if not properly tuned out.

The output circuit of the second tube 26 is connected to the winding 11 of the poly-phase relay MR through a blocking condenser 47, this circuit being obvious from the drawings.

Operation.—With both track and line phase currents flowing in the track rails, the two sets of receiving coils 8 and 9 have alternating voltages induced therein, and voltages are impressed upon the grid and filament circuits of the tubes 14 and 14¹ of the amplifiers L and T respectively. These alternating voltages are amplified by the tubes 14 and 14¹ in the usual manner and are impressed on the primary windings of the transformers 33 and 33¹ through the blocking condensers 36 and 36¹, these blocking condensers serving to prevent the direct current component from the plate circuits from passing through the transformer windings. The alternating voltages impressed upon the transformers are stepped up and impressed on the grid circuits of the tubes 26 and 26¹, and these voltages are again amplified and impressed on the windings of the relay MR, through the blocking condensers 47 and 47¹ and circuits which are obvious. Since the two alternating control currents flowing in the track rails are displaced in phase relation as pointed out above, the two amplified alternating currents flowing in the windings 10 and 11 of the relay MR are also displaced in phase relation, and a torque is produced in this relay in the usual manner, causing the contact fingers 10 and 11 to swing to the positions shown and to control the car-carried apparatus as described above.

Under danger traffic conditions, that is, with the train under consideration traveling in a block in which another train or other danger condition is located, the line phase current only is flowing in the track rails, the amplifier L alone is energized and the relay MR should be de-energized. As the voltage of a generator fluctuates with a fluctuation in load, the varying current drawn by the plate circuit of the amplifier L causes a fluctuation in the terminal voltage of the generator G, which in turn causes a fluctuation in the voltage impressed across impedance coil 30¹ and the first tube 14¹ of the track phase amplifier T. Ordinarily, with the usual type of amplifier, this fluctuation of the voltage in the plate circuit of the first tube of the amplifier T would be passed on by a transformer located in this plate circuit, and would cause a variation in the voltage impressed on the grid

circuit of the second tube 26¹, thereby impressing an alternating current from the amplifier T on the relay winding 10. This false or cross-feed current, as it is sometimes called, if out of phase with the current impressed upon the relay winding 11 by the amplifier L, produces a torque in the relay which may result in its operation, so giving a clear or caution indication under danger conditions. With the amplifier embodying the present invention, however, the grid circuit of the second tube 26¹ of the unenergized amplifier T is shielded from the fluctuation of the generator voltage by the high impedance of the coil 30¹ which tends to choke out such fluctuations before they reach the primary winding 38¹ of the transformer 33¹. Viewed in a different manner, the impedance of the coils 30, 31, 30¹, and 31¹ is very high as compared with the internal impedance of the tubes used, and for this reason, the voltage drop across the tube 14¹ and the primary winding 38¹ of the transformer 33¹ will be very small as compared with the voltage drop across the coil 30¹, and therefore a very small fluctuation in voltage will be passed on through the transformer 33¹ to the grid circuit of the second tube 26¹.

As the primary of the transformer 33 is connected directly across the plate and filament terminals of the tube 14, the variations in generator voltage are absorbed by the choke coil 30, but it should be observed that the variations in voltage across the tube itself caused by the alternating voltage impressed on its grid circuit from the collecting coils 9, are directly impressed upon the transformer 33 so that the tube and choke combination of the present invention may be said to pass on a maximum voltage from the grid circuit while choking back to a large extent, the voltage due to fluctuations in the plate circuit.

It is sometimes found that fluctuations or variations appear in the plate circuit voltage due to the characteristics of the generator used to supply this voltage, such as commutator ripples or variations due to mechanical vibration. It is evident from the discussion given above that such fluctuation would produce a false operation of the relay or an unreliable transmission of control influences from the trackway if the usual type of amplifier were used, but with the arrangement embodying the present invention, these fluctuations are choked out by the impedance coils as explained above and do not materially affect the operation of the relay.

It is obvious that in connecting the grid circuit of the second tube directly across the first tube, the voltage amplification which can be obtained from the first stage of amplification is dependent on the amplification characteristics of the tube used. In the amplifier embodying the present invention, the

voltage obtained from the first tube 14 is stepped up by means of the transformer 33 before being impressed upon the grid circuit of the second tube 26, so that an efficient voltage amplification may be obtained from the first stage.

In train control practice, the two control currents flowing in the track rails are unequal at certain points. For instance, at a point near 10 the exit end of a block, the track phase current in the track rails will be comparatively large because of the comparatively short path which this current traverses and the wheels and axis of the vehicle at this point, while at 15 the entrance of the block, the track phase current will be comparatively small due to the track rail resistance of the entire block. The line phase current, however, will be substantially constant throughout the entire 20 block. These unequal currents may produce a faulty operation of the car relay due to the fact that the stronger control current, flowing in one amplifier, produces fluctuations in the plate generator voltage in the manner described above, and these fluctuations, if applied to the other amplifier, may oppose the control current in such amplifier, thus weakening the current in one phase of the relay to such an extent that no torque will be produced 25 or reversing the phase relation between the currents and so giving a false indication. In the amplifier arrangement of the present invention, the fluctuation produced by the heavily energized phase cannot be impressed on 30 the weakly energized phase because of the shielding effect of the impedance coils 30 and 30¹ as described above, and for this reason, false relay operation as a result of unequal 35 control currents is avoided.

40 Amplifiers for use with train control systems must be balanced as to the constants of their various circuits in order to prevent false operation of the relays. That is, when two alternating voltages which are exactly in phase are impressed upon the two amplifiers, the currents which flow in the two windings of the relay must also be in phase in order that no torque will be produced in the relay. This condition is particularly necessary when 45 an unbalanced line phase control current flows in the two track rails in multiple, inducing voltages which are in phase in each of the receiving coils. In the usual type of amplifier, in order to transfer these alternating 50 control currents without phase displacement, the constants of the amplifier circuits must be uniform, and the various circuits must be carefully tuned. Due to the wide variation existing between the constants of commercial 55 tubes of a given type, it has been found that in the ordinary type of amplifier, when a tube was changed due to breakage or other failure, the constants of the amplifier circuits are so changed that the condition of balance 60 would not be maintained, and the amplifier

has to be tuned every time a new tube was inserted. In the amplifier comprising the present invention, this difficulty is eliminated by reason of the fact that the impedance of the tube is very small as compared with the impedance of the choke coils in the plate circuit, and hence a small change in the impedance of a given tube produces a negligible net change in the constants of the entire plate circuit. Because of this relation between 70 tube and coil constants, the tubes may be interchanged without the necessity of rebalancing the amplifier, and the internal tuning of the amplifier may be dispensed with.

The amplifier of the present invention is 80 particularly adapted for use with automatic train control systems for several reasons. It will not produce a false operation of the relay when one phase alone is energized. Commutator ripples or fluctuations in plate voltage 85 arising from any other source will not be amplified or impressed on the relay windings, whereas the impressed voltage received from the track rails will be efficiently amplified. Commercial variations in circuit constants, 90 such as variations caused by the interchanging of tubes, will not materially affect the operation of the amplifier.

As the amplifier of the present invention 95 has been shown and described in a rather specific form, it should be clearly understood that the invention is not limited to the form shown, and that various changes, additions and modifications could be made within the scope of the appended claims without departing from the spirit of the invention.

What it is desired to secure by Letters Patent is:—

1. In an automatic train control system, means for amplifying current inductively received from the trackway comprising, two audion tubes, inductive receiving means connected between the grid and filament of one of said tubes, a circuit connecting the plate and filament of said tube including in series a direct current generator and means for reducing voltage fluctuations, a second circuit connecting the plate and filament of said tube including the primary winding of a transformer, and a tuned circuit connecting the grid and filament of said second tube including the secondary winding of said transformer, whereby the voltage fluctuations of said direct current generator are not transmitted from the plate and filament circuit of said first tube to the grid and filament circuit of said second tube.

2. In an automatic train control system, means for amplifying current inductively received from the trackway comprising a plurality of audion tubes, inductive receiving means connected between the grid and filament of one of said tubes and means for connecting said tubes in cascade comprising circuits connecting the plates and filaments of

- each of said tubes including in series a direct current generator and an iron core impedance coil, a second circuit connected between the plate and filament of one of said tubes 5 including the primary winding of a transformer, and a tuned circuit including the secondary winding of said transformer connected between the grid and filament of another of said tubes.
- 10 3. In an automatic train control system, car-carried means for receiving and amplifying control currents comprising two sets of receiving coils connected by tuned circuits to the grid and filament elements of two 15 audion tubes, two parallel circuits connected to the plate and filament elements of each of said two tubes, one of said circuits including the primary winding of a transformer and the other of said circuits including an impedance coil and a common source of potential, and a circuit connected between the grid and filament elements of each of two other audion tubes, and each including in 20 multiple the secondary winding of one of said transformers and a variable condenser.
- 25 4. In an automatic train control system, means for collecting and amplifying two inductively received control currents comprising, two sets of receiving coils, connected respectively with the grid and filament circuits of two audion tubes, transformers having their primary windings connected across the plate and filament circuits of said two audion tubes and their secondary windings 30 tuned and connected to the grid and filament circuits of two other audion tubes respectively, circuits including a source of continuous potential connected in parallel respectively with the plate and filament circuits of all of said audion tubes, and impedance coils included in said potential circuits only.
- 35 40

to the plates of said tubes, said impedance coils being included in said potential circuits only.

5. In an automatic train control system, 45 means for collecting and amplifying two inductively received control currents comprising, two sets of receiving coils, connected respectively with the grid and filament circuits of two audion tubes, transformers having 50 their primary windings connected across the plate and filament circuits of said two audion tubes and their secondary windings tuned and connected to the grid and filament circuits of two other audion tubes respectively, 55 circuits including a source of continuous potential connected in parallel respectively with the plate and filament circuits of all of said audion tubes, and impedance coils included in said potential circuits only. 60

6. In an automatic train control system, means for amplifying current inductively received from the trackway comprising, two audion tubes, inductive receiving means connected between the grid and filament of one of said tubes, a circuit connecting the plate and filament of said tube including in series a direct current generator and means, having an impedance several times as great as that of a said tube, for reducing voltage fluctuations, a second circuit connecting the plate and filament of said tube including the primary winding of a transformer, and a tuned circuit connecting the grid and filament of said second tube including the secondary 75 winding of said transformer, whereby the voltage fluctuations of said direct current generator are not transmitted from the plate and filament circuit of said first tube to the grid and filament circuit of said second tube. 80

In testimony whereof I affix my signature.
WILLIAM D. HAILES.
